UNITED STATES PATENT OFFICE

132,010

DESIGN FOR A COMBINATION KITCHEN UNIT

Guyon L. C. Earle, Forest Hills, N. Y., assignor to
Genevieve M. Earle, Forest Hills, N. Y.

Application April 27, 1940, Serial No. 91,998

Term of patent 7 years

To all whom it may concern:

Be it known that I, Guyon L. C. Earle, a citizen of the United States of America, residing at Forest Hills, in the county of Queens and State of New York, have invented a new, original, and ornamental Design for a Combination Kitchen Unit, of which the following is a specification, reference being made to the accompanying drawings, forming a part thereof, and in which:

Fig. 1 is a perspective view of a combination kitchen unit, comprising a refrigerator, stove, dish strainer, sink and cabinets showing my new design in closed position; and

Fig. 2 is a perspective view thereof, in opened position.

The characteristic feature of my design resides in the fronts of all the sections in the intermediate portion lie in a plane positioned a substantial distance to the rear of the front panel sections of both the upper and lower units.

I claim:

The ornamental design for a combination kitchen unit substantially as shown and described.

GUYON L. C. EARLE.

Design No. 132,010.

CERTIFICATE OF CORRECTION.

April 14, 1942.

GUYON L. C. EARLE.

It is hereby certified that error appears in the printed specification of the above numbered patent requiring correction as follows: First column, line 12, for "strainer" read --drainer--; and that the said Letters Patent should be read with this correction therein that the same may conform to the record of the case in the Patent Office.

Signed and sealed this 23rd day of June, A. D. 1942.
